[57] CLAIM

The ornamental design for a smoke detector tester, as shown and described.

DESCRIPTION

FIG. 1 is a right front perspective view of a smoke detector showing my new design;

FIG. 2 is a front elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a left front perspective view thereof with the tube extended and the ash collector raised.

The showing of smoke and cigarette in broken lines in FIG. 7 is environmental only and form no part of the claimed design.

FIG. 5

FIG. 6

FIG. 1

FIG. 2

FIG. 4

FIG. 3

FIG. 7
